UNITED STATES PATENT OFFICE.

JENNIE L. ALLEN, OF LONG BEACH, CALIFORNIA.

DOLL.

1,261,931.

Specification of Letters Patent.

Patented Apr. 9, 1918.

Application filed January 30, 1917. Serial No. 148,904.

To all whom it may concern:

Be it known that I, JENNIE L. ALLEN, a citizen of the United States, residing at Long Beach, in the county of Los Angeles 5 and State of California, have invented new and useful Improvements in Dolls, of which the following is a specification.

My invention relates to character dolls and the primary object is to provide a doll 10 having a substantially elastic body composed of a trunk, legs, arms and head, all of which members are designed to be made and stuffed separately and thereafter stitched together.

15 The general characteristics of my doll are somewhat similar to the ordinary type of rag or cloth dolls, but as all of the members in my doll are made separately the general form and figure of the doll will be more 20 permanent and lasting because of the fact that in the ordinary rag dolls a single pattern is usually provided for the entire figure and the stuffing within the cloth body is usually continuous from one extremity to the 25 other.

It is, therefore, a further object of this invention to provide a doll in which the stuffing of the several members of the body may be separated so that by constant use and 30 handling the same may not be displaced from the members, thus distorting the figure.

A further object of this invention is to 35 provide a body having a covering of preferably knit material which will provide ample flexibility and elasticity so that the figure may be slightly contracted or extended for changing the form and also to permit the ready bending of the arms and legs without distorting the lines of the figure and for 40 retaining a more human like form than would otherwise be possible.

A further object is to provide a doll having the features and the hair embroidered on the head in different colors for providing 45 desired expressions. Other objects may appear in the following description.

Referring to the drawings, Figure 1 is a front view and Fig. 2 is a side view of my improved doll showing the body erect. Fig. 50 3 is a side view showing the body in a sitting posture with the legs extended horizontally.

In the consideration of this invention it should be understood that the method of cutting and stitching the members together 55 is as much a part of my invention as the completed doll, for the manner of attach-

ing the various members of the body together as shown is essential to the accomplishment of the objects set forth.

The trunk 1 is formed of a single piece of 60 knit material, which in original form, is substantially rectangular in shape and is sewed together on the side, as shown in Fig. 2, after it has been firmly stuffed in a manner similar to that of a pillow and there is 65 no opening left in the body through which the stuffing may protrude or work out. The head 2 is similarly formed, except that it is substantially spherical in its original form and the stuffing therein is entirely inclosed 70 within the covering. The neck portion of the head is stitched at 3 to the upper portion of the trunk 1. The mouth 4, the nose 5, the eyes 6, the eyebrows 7 and the hair 8 are 75 embroidered on the head as shown, in suitable colors and the pupils of the eyes may be embroidered at different positions for changing the expression.

The arms 9 are integrally made and stuffed and stitched entirely around their ends to 80 the upper side portions of the trunk at 10. The lower ends of the arms are reduced to form the hands 11 and the pieces from which the arms are made are cut at 12 on one side and then stitched together after the stuffing 85 is inserted. On the rear side of the arms a cut similar to that 12 on the front may extend from one end to the other. The manner in which the patterns for the arms are cut give form to the arms and by means of the 90 cut 12 therein the lower ends of the material which covers the arms may be drawn together so as to provide a suitable form therefor. The legs 13 are also formed of a single piece of material with cuts 14 at the back 95 extending from the heels 15 to the waist line 16 and a shorter cut 17 is provided in the front which serves the same purpose as the cuts 12 in the arms.

The edges of the material at the cuts 14 100 and 17 are stitched together in a manner similar to that of the arms and by means of this stitching the material may be drawn together so as to provide the proper form for the feet 18, the upper ends of the legs 13 105 are stitched together for inclosing the stuffing therein and they are also stitched entirely around the periphery of the legs at the point 19 and the waist line 16 to the trunk 1. It will be observed that the upper 110 portions of the legs 13 are substantially extended at the rear upwardly to the waist

line 16 and substantially above the abdominal portion 20 of the trunk 1, so that when the legs are extended horizontally as shown in Fig. 3, a more human like form will be provided. It will be understood that were the legs 13 attached to the trunk 1 at but a single point, as in the case of the ordinary cloth dolls, such a form as shown in Fig. 3 would be impossible.

10 Inasmuch as all of the members are made and stitched separately and the stuffing in each of the members when attached together is separated it will be impossible for the form of any of the members to become distorted from use. On the other hand the stuffing, which is preferably of cotton, being firmly, but not too solidly, packed in the limbs will permit the bending of the limbs at the knee and elbow joints. The bending 15 of the limbs is further permitted by means of the elastic quality of the knit material from which the limbs and body are made and this material is essential for the accomplishment of the objects set forth, for it is obvious that were cloth, such as muslin or linen or other close woven material used 20 for inclosing the stuffing, it would not generally be possible to bend the limbs in such a manner. When the proper quality of knit material is used the limbs will usually retain any desired form. The manipulation 25 of the stuffing in the several members of the body will permit the changing of the positions and form of the members for different 30 postures.

I am aware that patents have been issued

for dolls having bodies of cloth and having the features embroidered thereon but I am not aware that anyone has heretofore known or used dolls embodying the improvements set forth in the foregoing specification and I desire to claim broadly thereon.

Having thus described my invention what I claim is:—

1. A character doll having separately 45 stuffed and inclosed head, trunk and limb members, facial features, and the leg members having an upwardly and rearwardly extending curve terminating in a horizontal shoulder portion, as set forth.

2. A character doll having separately 50 stuffed and inclosed head, trunk and limb members, the abdominal portion of said trunk member being extended beyond the rear portion thereof forming a recess, and 55 the leg members being extended into and attached to said trunk member at said recess.

3. A character doll having separately 60 formed trunk, head, arm and leg members stitched together, said leg members having upwardly extending portions at the rear for attachment to said trunk portion at points above the points of attachment of the front portions thereof.

Signed at Los Angeles, in the county of Los Angeles, and State of California, this 6th day of Nov., 1916.

JENNIE L. ALLEN.
